UNITED STATES PATENT OFFICE.

KENNETH A. CLANCY, OF PORTLAND, OREGON.

BOTTLE CARRIER.

Application filed October 21, 1925. Serial No. 63,935.

This invention relates to improvements in bottle carriers, and has for its principal object to provide a simple and efficient article which may be readily and easily adjusted to accommodate bottles or other receptacles to be carried of various sizes.

One of the important objects of the present invention is to provide a bottle carrier which is formed of a single elongated strip 10 of flexible material, the same being provided with a receptacle engaging loop, which loop is adjustable to accommodate receptacles of various sizes, said strips further being provided with a handle to facilitate the 15 transportation for carrying of the receptacle from place to place.

A still further object is to provide a bottle carrier of the above mentioned character which is simple in construction, inexpensive, strong and durable and further well 20 adapted to the purpose for which it is designed.

Other objects and advantages of the invention will become apparent during the 25 course of the following description taken in connection with the accompanying drawing.

In the accompanying drawing forming a 30 part of this application and in which like numerals designate like parts throughout the same:—

The figure represents a perspective view 35 of my improved bottle carrier showing the manner in which the same is associated with the neck of a bottle.

In the drawing wherein for the purpose 40 of illustration is shown the preferred embodiment of my invention, the numeral 1 designates generally my improved bottle carrier, the same being formed of a single 45 elongated strip of flexible material, preferably leather, although any other material may be substituted therefor. The elongated strip of leather is looped intermediate its ends as illustrated at 2 and the end portions 50 3 and 4 are provided with longitudinally extending slits 5 and 6 respectively at a point adjacent the looped portion 2 and the purpose of these slits will be presently apparent.

The free end of the end portion 3 of the strip is adapted to extend through the slit 6 formed in the end portion 4, while the end portion 4 has its free end extending 55 through the opposed slit 5, so as to form a bottle engaging loop 7 which extends

around the neck of a bottle, and it is obvious that by actuating the end portions of the strip of leather, the size of the loop 7 may be increased or reduced, depending 60 upon the size of the neck of the bottle around which the looped portion of the carrier is adapted to extend and by pulling outwardly on the end portions of the strip of leather, the looped portion will be drawn 65 tightly around the receptacle so that a binding relation is formed to prevent the accidental displacement of the receptacle from the carrier.

The end portions 3 and 4 of the strip are 70 disposed upwardly after passing through the slits 5 and 6, and the free ends of the end portions are disposed inwardly and secured together as illustrated at 8 to provide a handle 9 for facilitating the carrying 75 of the receptacle after the looped portion 7 is in engagement with the receptacle.

In the present instance, the bottle carrier is shown as being associated with the neck 80 of the bottle, although it is to be understood that the carrier may be also used in connection with other receptacles in a similar manner.

The simplicity in which my bottle carrier is constructed enables the same to be readily and easily adjusted with respect to the receptacle with which the same is to be associated, and will at all times be positive and efficient in carrying out the purposes for 85 which it is designed.

While I have shown the preferred embodiment of my invention it is to be understood that minor changes in the size, shape and arrangement of parts may be resorted to without departing from the spirit 90 or scope of the appended claims.

Having thus described the invention, what I claim as new and desire to secure by Letters Patent is:—

1. A bottle carrier formed of a single 100 elongated strip of flexible material looped intermediate its ends, the end portions of the strips having slits formed therein adjacent the looped portion, the free ends of the strips adapted to extend through the 105 opposed slits to provide an adjustable bottle engaging loop.

2. A bottle carrier formed of a single 110 elongated strip of flexible material looped intermediate its ends, the end portions of the strips having slits formed therein adjacent the looped portion, the free ends of

- the strips adapted to extend through the opposed slits to provide an adjustable bottle engaging loop, the free ends of said strips being secured together to provide a handle.
- 5 3. As an article of manufacture, a bottle carrier formed of a single elongated strip of flexible material, the intermediate portion of said strip being provided with a pair of spaced longitudinally extending slits, one
10 of the free ends of the strips adapted to extend through one of said slits, the other free end of the strip adapted to cross the other end portion of the strip and extending through the other slit to provide an adjustable bottle engaging loop.
- 15 4. As an article of manufacture, a bottle carrier formed of a single elongated strip of flexible material, the intermediate portion of said strip being provided with a pair
20 of spaced longitudinally extending slits, one

of the free ends of the strips adapted to extend through one of said slits, the other free end of the strip adapted to cross the other end portion of the strip and extending through the other slit to provide an adjustable bottle engaging loop, the free ends of the strip being secured together to provide a handle.

25 5. As an article of manufacture, a bottle carrier formed of a single elongated strip of flexible material, said strip being provided with a longitudinally extending slit in the intermediate portion thereof, one of the free ends of the strip adapted to pass through the slit to provide an adjustable bottle engaging loop, the free ends of the strip being secured together to provide a handle.

30 In testimony whereof I affix my signature.
35 KENNETH A. CLANCY.
